US0D1101721S

(12) **United States Design Patent** (10) Patent No.: **US D1,101,721 S**
(45) Date of Patent: ** Nov. 11, 2025

(54) **MEDIA PLAYER DEVICE**(71) Applicant: **Sonos, Inc.**, Santa Barbara, CA (US)(72) Inventors: **Daehoo Kim**, Oxnard, CA (US);
Vincent Shyu, Santa Barbara, CA (US);
Aki Laine, Santa Barbara, CA (US);
Dana Krieger, Santa Barbara, CA (US)(73) Assignee: **SONOS, INC.**, Goleta, CA (US)(**) Term: **15 Years**(21) Appl. No.: **29/792,761**(22) Filed: **Apr. 21, 2022**

CLAIM

The ornamental design for a media player device as shown and described.

DESCRIPTION

FIG. 1 is a front elevation view of a media player device, showing our new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a perspective view thereof; and,

FIG. 8 is a second perspective view thereof.

The features shown in dash-dash broken lines do not form part of the claimed design.
